UNITED STATES PATENT OFFICE.

WALTER F. LUHNOW, OF OAK PARK, ILLINOIS.

SOUND AMPLIFIER.

1,420,719.

Specification of Letters Patent. Patented June 27, 1922.

Application filed March 1, 1920. Serial No. 362,245.

To all whom it may concern:

Be it known that I, WALTER F. LUHNOW, a citizen of the United States of America, and a resident of Oak Park, county of Cook, and 5 State of Illinois, have invented certain new and useful Improvements in Sound Amplifiers, of which the following is a specification.

This invention relates to means for modulating and amplifying sound, as for instance, in sound recording devices and especially in phonographs. It follows in a large measure the lines of my copending applications, Serial No. 349,444 filed January 5, 1920, and Serial No. 357,300 filed February 9, 1920, but is distinct therefrom particularly respecting the structure of the amplifying chamber or horn.

The main objects of the invention are to 20 provide for enriching the tones to be recorded or reproduced; to provide amplifying means of improved form in connection with sound recorders and reproducers to selectively pick up and amplify the tones and 25 qualities desired; and to provide such a device adapted for use in various forms in combination with a recorder or reproducer, either in a cabinet or apart therefrom.

An illustrative embodiment of this invention is shown in the accompanying drawings, in which—

Fig. 1 is a view of a complete phonograph partly in side elevation with the upper part in vertical section through the center from front to back.

Fig. 2 is substantially a horizontal section through the branched end of the amplifying chamber on the line 2—2 of Fig. 1.

Fig. 3 is an underside view of a modified 40 form of branched amplifying chamber.

Fig. 4 is similar to Fig. 3 except as to the form and arrangement of the branches.

Fig. 5 is an axial section through a modified form of amplifying chamber or circular cross-section with branches distributed 45 about the main axis, and the sound admission tube being connected directly opposite the end of the inner part of the chamber.

Fig. 6 is a section on the line 6—6 of 50 Fig. 5.

Fig. 7 is a front elevation of the sound discharge end of the amplifying chamber.

Fig. 8 is an axial section of a bell-shaped chamber having a stepped inner wall.

Fig. 9 is a side elevation of a horn with a 55 medial sound inlet and with open-ended

amplifying branches shown in dotted lines.

In the construction shown in Fig. 1, the reproducer 1 is carried by a pivotally mounted arm 2 communicating with the 60 amplifying chamber or horn 3, said parts being mounted in a cabinet 4.

Said chamber 3 is of oblong shape and for convenience and saving of space in mounting in the cabinet is folded medially, 65 the large wide-mouthed end 5 being disposed above the small end 6. The point of communication for said arm 2 and chamber 3 is at 7 on the side of the large end 5 near the central point or bend of said chamber. 70

The lower part or smaller end 6 of said chamber is branched or furcated as shown, for instance, in Fig. 2. In this instance, there are two main mutually complementary branches 8 extending from the 75 curved middle part of the chamber. Each branch 8 is forked centrally, branches 9 being provided as shown. Said branches 9 in turn are forked centrally, whereby further branches 10 are provided.

In the form of amplifying chamber shown in Fig. 3, the horn 12 has a small end 13 and a large end 14. The small end comprises two mutually complementary branches 15, each of which is provided with a series 85 of smaller branches 16, ranging in length from very short branches to branches of nearly the full length of the arms 15.

In the form shown in Fig. 4, the small end 17 of the amplifying chamber is also 90 furcated, the large end 18 being like the above described parts 5 and 14. The branches in this instance are successive, that is to say, first there are two large complementary branches 19, here shown as similar, 95 each of which in turn divides into a pair of complementary branches 20; then again each branch 20 divides into a pair of complementary branches 21. The horns shown in Figs. 1, 2, 3 and 4 may all be similar except as above specified.

In the form shown in Figs. 5, 6 and 7, the amplifying chamber or horn 22 is circular in cross-section and is closed at the rear end 23 except for a central sound passageway 24 communicating with the tone arm, reproducer or recorder, as may be required. Said chamber is provided with a central conoidal wall 25 in alinement with the sound inlet 24 and flaring outwardly toward the discharge end 26. The space between the outer and inner walls 27 and 25 is

divided by radial partitions 28, which may extend the full length of the wall 25. The concentric sound chambers or parts of the one continuous chamber constitute substantially a flaring amplifier, nearly closed at the annular end 29 and wide open at the opposite end 26. This structure is substantially of a similar acoustic character with the branched horns shown in Figs. 2, 3 and 4, but differs structurally in that in this instance the small branched end of the horn is disposed concentrically about the large end of the horn instead of only at one side thereof.

15 In the form shown in Fig. 8, the structure of the amplifying chamber as a whole is bell-shaped and more nearly resembles the form shown in Fig. 5 than any other embodiment here illustrated. In this instance, the larger end of the chamber is enclosed by a flaring wall 30 outside of which is disposed the branched small end of the amplifying chamber. The outer wall 30 of the restricted part of the chamber is also of bell shape, but is less flaring than the inner wall 30, so that the radial depth of the amplifying chamber as a whole diminishes from the large main sound outlet end 32 inward to the point of curvature 33 and then out to the open tip shown at 34.

The sound inlet tube 35 is connected to the outer wall 31 coaxially therewith and extends inward somewhat past the adjacent edge of the inner wall 30. The inner end of said tube is flared somewhat as at 36, and the outer end communicates with the reproducer substantially as shown in Fig. 1. The inner wall is formed with a series of circumferential steps 37, each of cylindrical shape, and connected by a radial web part 38 to the next adjacent step, so that the inner or large area end of the chamber is enclosed by a wall having outwardly facing shoulders, and the more restricted outwardly disposed small end of the chamber is provided with similar shoulders 39 facing inwardly, as a result of which all sound vibration is reflected and urged toward the discharge end or mouth 32 of the main central part of the chamber.

Any vibration or impelling action which may occur, due to the facing of the shoulders or steps 37 and 39 will be in a like direction, that is to say, from the small end 34 inward and thence out at the large

end 32. This applies both to the sound and to the sound medium, even though the effect on the latter may be negligible. In order to improve the modulating effect of this form of chamber, a plurality of radially disposed walls 40 are distributed in the outer space or chamber, extending from a point near the inner bend 33 outward to the edge 34.

In the form shown in Fig. 9, the elongated or oblong horn 41, which is open at both ends, has a flaring discharge end 42 and a divided narrower end 43, the sound inlet 44 being medial and about opposite the inner end of the shortest chamber furcation 45. Other furcations vary in length, the outermost and longest 46 being nearly the full length of the horn.

In each of the forms shown, stops or plugs 47 may be provided to close one or more of the furcation tips as shown in connection with Fig. 2, as may be desired at times. This assortment of amplifying branches and stops therefor permits selective picking up and amplification of the qualities and tones desired.

Although several specific embodiments of this invention are herein shown and described, it is to be understood that some of the details of the constructions shown may be altered or omitted without departing from the spirit of this invention as defined by the following claims.

I claim:

1. A sound amplifying chamber of oblong shape, mainly conoidal, and furcated at the smaller end, the large end and one or more of the branch tips being open.
2. A sound amplifying chamber of oblong shape, mainly conoidal, and furcated at the smaller end, the large end and one or more of the branch tips being open, and a side aperture being provided medially to admit the sound to be amplified.
3. A sound amplifier in the form of an oblong chamber having a sound inlet near its center; said chamber in one direction from said inlet being of flaring form and open, and in the other direction being of restricted and convergent form with a plurality of open tipped branches or furcations having removable closure means.

Signed at Chicago this 24th day of February, 1920.

WALTER F. LUHNOW.
